UNITED STATES PATENT OFFICE.

CHRIST MINEART, OF EAST PLEASANT PLAIN, IOWA.

CAR-BRAKE.

1,036,878.

Specification of Letters Patent. Patented Aug. 27, 1912.

Application filed April 22, 1912. Serial No. 692,417.

To all whom it may concern:

Be it known that I, CHRIST MINEART, a citizen of the United States, residing at East Pleasant Plain, in the county of Jefferson and State of Iowa, have invented a new and useful Car-Brake, of which the following is a specification.

The invention relates to improvements in car brakes.

10 The object of the present invention is to improve the construction of car brakes, and to provide a simple, inexpensive and efficient car brake of great strength and durability, adapted to be applied to any ordinary truck, 15 and equipped with means for preventing the brake beams from dropping down upon the rails.

With these and other objects in view, the invention consists in the construction and 20 novel combination of parts hereinafter fully described, illustrated in the accompanying drawings, and pointed out in the claims hereto appended; it being understood that various changes in the form, proportion, 25 size and minor details of construction, within the scope of the claim, may be resorted to without departing from the spirit or sacrificing any of the advantages of the invention.

30 In the drawings:—Figure 1 is a central vertical longitudinal sectional view of a car truck, equipped with a brake, constructed in accordance with this invention. Fig. 2 is a 35 plan view of the same. Fig. 3 is a reverse plan view. Fig. 4 is a vertical sectional view taken on the line 4—4 of Fig. 2, and illustrating the arrangement of the guards.

Like numerals of reference designate corresponding parts in all the figures of the 40 drawings.

In the accompanying drawings in which is illustrated the preferred embodiment of the invention, 1—1 designate inside brake beams of the truss type, suspended by suitable hangers 2 from the upper portion of 45 the truck at opposite sides of the bolster 3 thereof, and operating in the space between the spring plank 4 and the car wheels 5. The brake beams are supported above the 50 plane of the lower face of the spring plank and prevented from dropping below the same by means of approximately horizontal guards 6, extending across the lower face of the spring plank and projecting outwardly beyond the side edges thereof and 55 having their projecting portions arranged

beneath the brake beams. The guards 6, which are located at opposite sides of the truck, consisting of bars or pieces of channeled metal, or other suitable material, and 60 they are secured to the spring plank by vertical bolts 7, piercing the spring plank and the guards and having nuts 8 arranged between the side flanges 9 of the guards. The side flanges of the guards depend from the 65 same, and the upper faces of the guards are flat between the terminals 10; which are extended upward slightly.

The guards besides preventing the brake beams from dropping upon the rails enable 70 them to be arranged in a position, which will admit of the employment of a relatively straight inclined connecting bar 11 having a slight bend 12 near its lower end, and connected at its upper end 13 with an 75 upright lever 14. The connecting rod and the lever are arranged centrally of the truck, and the rod extends through the space between the spring plank and the bolster, and its downwardly extending terminal portion 80 is pivoted by a bolt 15, or other suitable fastening device in the central strut member 16 of the adjacent beam. The lower end of the upright lever 14 is pivoted by a bolt 16, or other suitable fastening device in 85 the bifurcation of the strut member of the other brake beam, and the end 13 of the connecting rod is forked or bifurcated to receive the lever 14, and is provided with a plurality of perforations 17 for the reception 90 of a bolt 18, or other suitable fastening device to afford an adjustable connection between the brake beams.

The upper end of the upright lever 14 is connected by a rod 19 with the brake operating mechanism, and when the said upper end of the lever 14 is moved toward the bolster of the truck, the brake shoes 20 of both the brake beams are carried into engagement with the car wheels. Owing to 95 the particular arrangement of the brake beams, a connecting rod 11 of great strength amply sufficient to withstand the thrust strain may be employed as the rod 11 is straight throughout the major portion of 100 its length and has only a slight curvature at one end.

What is claimed is:—

The combination with a car truck, of 110 brake beams located at opposite sides of the spring plank and arranged above the plane of the lower face of the same and operating

between the spring plank and the car wheels, an upright lever connected at its lower end with one of the beams and extending upwardly therefrom, and an inclined connecting rod extending from the lever through the space between the spring plank and the bolster and connected with the other brake beam, said rod being provided adjacent to the latter brake beam with a slight bend and

being straight from the bend to its other end.

In testimony, that I claim the foregoing as my own, I have hereto affixed my signature in the presence of two witnesses.

CHRIST MINEART.
